UNITED STATES PATENT OFFICE.

LANSING ONDERDONK, OF BOSTON, MASSACHUSETTS, ASSIGNOR TO THE UNION SPECIAL SEWING MACHINE COMPANY, OF CHICAGO, ILLINOIS.

LOOPER MECHANISM FOR SEWING-MACHINES.

SPECIFICATION forming part of Letters Patent No. 591,545, dated October 12, 1897.

Application filed July 18, 1896. Serial No. 599,689. (No model.)

To all whom it may concern:

Be it known that I, LANSING ONDERDONK, a citizen of the United States, residing at Boston, in the county of Suffolk, State of Massachusetts, have invented certain new and useful Improvements in Sewing-Machines, of which the following is a description, reference being had to the accompanying drawings and to the letters of reference marked thereon.

My invention relates to an improvement in sewing-machines, more especially to the double-chain-stitch type; and the object is to provide improved means for adjusting the under-thread-carrying looper whereby the distance of its loop-taking point from the needle and consequent time at which it takes the loop may be varied, or its lateral movement with respect to the needle may be changed to give greater or less sidewise throw on one side of the needle than on the other.

The invention consists in the matters hereinafter described, and referred to in the appended claims.

It is illustrated in the accompanying drawings, in which—

Figure 1 is a side view of so much of a sewing-machine as is necessary to illustrate the relations of the parts. Fig. 2 is a top plan view of a looper-carrier constructed in accordance with my invention. Fig. 3 is a side view showing a slightly different form of looper-carrier. Fig. 4 is a side view of Fig. 1. Fig. 5 is a detail view of a looper adapted for adjustment. Fig. 6 is a plan view showing a diagonal adjustment for the looper on the carrier.

In the drawings, A represents the sewing-machine needles, and B the under-thread-carrying looper, supported on a suitable carrier C, which, as herein shown in Fig. 1, has an oscillating and sliding movement imparted to it by an inclined crank connection with the driving-shaft of the machine, and in Fig. 3 by a crank and eccentric. This looper-carrier C is, as shown, provided with a block D, which is formed to fit a dovetailed groove in the carrier, or the carrier may be provided with a series of holes adapted to register with a hole in the block D, or the two may have registering slots, and in all these instances

when the block has been adjusted to its desired position set-screws E, passing through the block, are tightened and serve to hold the block securely in place.

The block D is provided with a socket or eye F, in which the shank G of the looper B is inserted.

If desired to secure only a lateral adjustment of the looper, the shank thereof may be vertical, fitting in a vertical socket on the block D, but if desired to secure an adjustment for regulating the time of entry of the looper into the needle-loop I preferably make the socket or eye horizontal and bend the shank of the looper so that it lies horizontally and is secured in said eye by means of a set-screw and having a flattened end to afford a better binding-surface for the end of the screw. To adjust the looper lengthwise, therefore, it is necessary only to move its shank forward or back in the eye. By this means I am enabled to position the looper in its carrier so as to cause a quick or slow co-operation of the looper with the needle-loops, accordingly as long or short needles are used or the needle mechanism causes a long or short "dwell" of the needle.

In Fig. 6 is shown an arrangement for providing an adjustment when it is desired to arrange the looper to oscillate in a plane at an oblique angle to the plane of its carrier-block D, or other plane in which said block is vibrated, or the plane in which said block is adjustable in the looper-carrier. In this construction the block D is adjustable in the manner above described on the looper-carrier C by screws E, and a second block D' is adjustable upon block D by means of curved slots G² and adjusting-screws G'. The block D' also carries a looper-socket F, secured thereto by screws, and the stem of the looper is adjustable in said socket, as described in connection with the other figures. The curvature of the slots G² and their disposition are such as to provide a relative lateral adjustment of block D' of considerable extent.

Having thus described my invention, what I claim as new, and desire to secure by Letters Patent, is—

1. A looper mechanism for sewing-machines comprising a looper-carrier; a block

having an adjustable connection therewith; and a looper having an adjustable connection with the block, the latter adjustment being substantially at right angles to the former, substantially as described.

2. A looper mechanism for sewing-machines, comprising a looper-carrier; a looper supported by said carrier; and means for securing two bodily, right-line adjustments of said looper relative to its carrier, substantially at right angles to each other, substantially as described.

3. A looper mechanism for sewing-machines, comprising a looper-carrier; a block having an adjustable connection therewith; a second block having an adjustable connec-

tion with the first block; and a looper carried by said second block, substantially as described.

4. A looper mechanism for sewing-machines, comprising a looper-carrier; two blocks supported by said carrier; means for adjusting said blocks relative to the carrier and to each other; the adjusting means between the two blocks being a pin-and-slot connection, substantially as described.

In testimony whereof I affix my signature in presence of two witnesses.

LANSING ONDERDONK.
